UNITED STATES PATENT OFFICE

GEORGE N. PIFER, OF CLEVELAND, OHIO, ASSIGNOR, BY MESNE ASSIGNMENTS, TO AMERICAN PHOTOTURE COMPANY, OF NEW YORK, N. Y., A CORPORATION OF DELAWARE

PROCESS FOR MAKING COLORED PHOTOGRAPHS

Application filed April 22, 1927. Serial No. 185,681.

This invention relates to a process of making colored photographs and has especial utility in connection with an automatic photographing machine, such as constitutes the subject matter of my prior application Serial No. 758,989, filed December 31, 1924, the present invention in one aspect being an improvement on the developing method disclosed therein.

10. In the automatic photographing machine of my prior application, positive pictures are produced in the following manner: An exposure is first made on a portion of a continuous film supplied from a spool, and the 15 exposed portion of the film is then shifted by a movement of the film into a chamber where the exposed surface is developed, fixed and washed. Then a card having a sensitized surface is fed to a position for exposure and subsequent development. The exposure is made 20 from the film and the exposed surface is developed, fixed and washed to produce the finished positive picture.

Both in the development of the negative 25 and in the development of the positive picture, a novel process is used wherein aerated developing, fixing and washing solutions are directed onto the exposed surface. These solutions are supplied from three receptacles, 30 each of which is provided with a discharge nozzle, and the solutions are selectively discharged from these nozzles and directed in aerated form onto the exposed surface, this being accomplished by causing a stream of air

35 to be directed successively across the ends of the nozzles. In practice, there is directed onto the exposed surface first an aerated stream or spray of developing solution, then an aerated washing solution, then an aerated 40 fixing solution, and finally the aerated washing solution. This same developing process is applied to both the negative and the positive pictures through two sets of nozzles.

I have discovered that by this same process, 45 with the addition of suitably colored washing solutions, very beautiful colored photographs can be produced, there being used preferably but not necessarily two colored washing solutions in producing the positive 50 picture.

The process will be explained more fully in connection with the accompanying drawing, the single figure of which shows conventionally or diagrammatically the manner in which the process is carried out in the production of a positive picture.

In the drawing, I have shown at 10 a card having a gelatinized or sensitized portion 11, which it will be assumed has been exposed and is ready for development. If the invention is used in the automatic photographing machine, it may be assumed that this is the card on which the positive picture is made from the negative which may have been developed in the same or substantially the same 65 way as the development which is to take place on this card.

The solutions used in the developing process are supplied from suitable receptacles, of which four are here illustrated and designated 12, 13, 14 and 15. If four receptacles are used, as is sometimes preferred, one will contain the developing solution, another the fixing solution, and the other two washing 70 solutions of two different colors, as, for example, red and yellow, which when used successively in the developing process employed in producing the positive picture I find cause 75 a very pleasing flesh color.

The receptacle 13 may contain the developing solution, the receptacle 14 the red colored washing solution, the receptacle 15 the fixing solution, and the receptacle 12 the yellow colored washing solution.

As here illustrated, the receptacles 12 to 15 85 are shown as bottles which are inverted, so that the solutions may stand at a given height in receiving receptacles 16, each of which is connected by a tube 17 to a delivery portion 18 from which extends a delivery tube 19 terminating in a nozzle. The four nozzles are arranged in line close to each other, these being designated 12^a, 13^a, 14^a and 15^a. It is obvious 90 that as long as there is solution in the bottles or receptacles 12 to 15 the solution will stand 95 at a given height in the receiving receptacles 16 and at the same height in the delivery receptacles 18.

Aerated solutions are caused to be discharged successively from the different 100

nozzles by the following means. Air is supplied under suitable pressure from a tube or pipe 20 and is led to a casing 21 containing four air nozzles 22 which are arranged so as to deliver blasts of air across the ends of the 5 solution delivery nozzles 12^a, 13^a, 14^a and 15^a. Slidable in the casing 21 is a distributor 23 in the form of a plunger having on one side an elongated slot 24 which at all times registers with the air supply tube 20 and having on the opposite side a port 25 which is adapted to be moved into registration successively with each of the four air nozzles 22. The air nozzles 22 are so arranged with respect to each other as well as with respect to the solution 10 delivery nozzles, that as the streams of air are directed over the same aerated solutions will be directed onto the exposed sensitized surface, as indicated in the drawing, this being true regardless of from which pair 15 of cooperating nozzles the solution and air are being delivered, it being assumed, of course, that the surface on which the solutions are to be directed will have a given position with respect to the nozzles.

In carrying out the process, the distributor 23 will first be so positioned as to cause the aerated developing solution to be directed onto the exposed surface. This is done by 20 positioning the plunger so that the port 25 is brought into registration with the air nozzle 22 at the end of nozzle 13^a. Next, the distributor is moved so as to bring the port 25 into registration with air nozzle which 25 is over solution delivery nozzle 14^a so as to cause a colored washing solution from receptacle 14 to be delivered onto the surface. Next, it is moved so as to bring the port 25 into registration with the air nozzle 22 so as 30 to cause an aerated fixing solution to be directed onto the surface. This can be accomplished by giving the distributor successive movements in the same direction. Then a colored washing solution is again applied, 35 this being preferably from receptacle 12 so as to cause the surface to be washed with a different colored washing solution. To do this, the distributor 23 is moved back until port 25 is in registration with the air nozzle 22 associated with solution delivery nozzle 12^a. The developing now having been completed, 40 the distributor is moved so as to place the port 25 in neutral position. It will be seen from the above that first an aerated developer is sprayed onto the sensitized surface, quickly 45 followed by an aerated washing solution, then by an aerated fixing solution, and finally by another aerated washing solution.

Let it be assumed that the receptacle 14 50 contains water colored red with a suitable dye and that receptacle 12 contains water colored yellow with a suitable dye. Accordingly, after the developer is applied, the developed surface is rinsed with a colored wash which 55 will give a red tint to the surface, and after

the application of the fixing solution the surface is rinsed with a yellow wash. This, I find, will leave the finished picture with a very pleasing flesh colored tint.

I do not, of course, desire to be confined to the use of the particular colors referred to, nor in fact to a combination of colors, for in some instances a single colored washing solution can be employed, in which event the colored wash can be applied after the application of the fixing solution or after the application of both the developing and fixing solutions. If the same washing solution is used following the application of the developing and fixing solutions, three receptacles 70 only will be necessary, otherwise four will be required if a combination of two colors is desired. It may be desirable to employ plain or uncolored water for the wash following the application of the developing solution, in which event the washing solution of the desired color or washing solutions of two different colors will be applied following the application of the fixing solution. All of these modifications I regard as coming within 75 the scope of my invention.

In the use of this process in an automatic photographing machine, such as shown in my prior application, one set of receptacles 80 only will be needed for the development of the negative and for the development of the image of the positive picture, but two sets of nozzles will be employed, the solution delivery nozzles of the two sets receiving solutions from the same group of receptacles, and, 85 of course, two sets of air nozzles will be employed. The air distributors or plungers 23 of the two sets will be automatically operated so as to cause the different aerated solutions to be applied in the right sequence onto the 90 exposed negative and onto the exposed positive.

In the development of the negative, solutions from three of the receptacles only are 95 needed, and if it be assumed that two different colored washing solutions are employed, such, for example, as red and yellow, which were the colors first mentioned, the yellow wash will be omitted and the surface of the negative will be washed with the red solution after 100 the application of both the developing and the fixing solutions. This will give the negative a red tint which, if a suitable red is employed and if the solution is sufficiently diluted, does no harm in so far as the exposure 105 on the positive is concerned, although it may slow up the printing action very slightly since the correct red color does not materially affect the passage of actinic rays through the negative to the sensitized surface of the positive. However, my invention is not so important in the development of the negative as it is in the development of the positive, 110 and a colored washing solution is employed in the development of the negative in order to 115

employ in the automatic photographing machine only the minimum number of solution receptacles in the completion of the cycle of operations of the machine for the production of colored photographs.

5 Having thus described my invention, I claim:

1. The process of producing a colored photograph which comprises developing an exposed surface and utilizing a colored washing solution in the developing process.

10 2. The process of producing colored photographs which comprises applying to an exposed sensitized surface developing and fixing 15 solutions and a colored washing solution.

3. The process of making colored photographs which comprises developing an exposed sensitized surface and utilizing in said development a plurality of differently colored 20 washing solutions.

4. The process of making colored photographs which comprises developing an exposed sensitized surface by subjecting it to the action of different solutions including an 25 atomized colored washing solution.

5. The process of making colored photographs which comprises developing an exposed sensitized surface by directing thereon atomized developing and fixing solutions and 30 an atomized colored washing solution.

6. The process of making colored photographs which comprises developing an exposed sensitized surface by directing thereon atomized developing and fixing solutions and 35 two differently colored atomized washing solutions.

7. The process of making colored photographs which comprises developing an exposed sensitized surface by directing thereon 40 successively an atomized developing solution, an atomized washing solution of one color, an atomized fixing solution, and an atomized washing solution of another color.

In testimony whereof, I hereunto affix my 45 signature.

GEORGE N. PIFER.
